COMBINATION BEAM PLATE AND OUTER SHIELD

Clifford M. Morris, Hackensack, N. J., assignor to Radio Corporation of America, a corporation of Delaware

Application March 14, 1955, Serial No. 494,111

14 Claims. (Cl. 313—299)

This invention relates to electron tubes, and more especially it relates to novel electrode structures and arrangements for such tubes.

A principal object of the invention is to provide a novel composite electrode and shield for electron tubes wherein electrostatic shielding between certain electrodes is a requisite.

Another object is to provide a novel composite beam defining a secondary electron collector electrode for grid-controlled electron tubes.

A further object is to provide a novel electrode configuration and arrangement which is especially useful in so-called pentode or beam power tubes.

A feature of the invention relates to an improved electrode which can be economically manufactured from sheet metal so as to form a composite beam-defining and secondary electron suppressor electrode.

Another feature relates to a novel beam plate or suppressor electrode for pentodes and beam power tubes of the dual interconnected anode kind, which plate or electrode can be readily assembled around a respective anode for shielding it completely except at the region where it is to receive electrons from an associated cathode. As a result of this feature, it is possible to manufacture such a mount with electrostatically shielded anodes while leaving the region intervening between the anodes and occupied by one or more grids, open to visual inspection.

Another feature relates to a novel composite shielding and beam-defining plate for electron tubes which enables small tubes such as so-called miniature tubes to be assembled and readily inspected during assembly for grid alignment, pushed grid turns, and the like.

A still further feature relates to the novel organization, arrangement, and relative configuration and location of parts which cooperately constitute an improved pentode or beam power tube.

Other features and advantages will appear as the ensuing specification proceeds.

In the drawing, which shows typical exemplifications, Fig. 1 is an elevational view of an electron tube according to the invention;

Fig. 2 is a sectional view of Fig. 1 taken along the line 2—2 thereof and viewed in the direction of the arrows;

Fig. 3 is an enlarged perspective view of one of the composite electrodes of Fig. 1;

Fig. 4 is a sectional view of Fig. 1 taken along the line 4—4 thereof and viewed in the direction of the arrows;

Fig. 5 is a sectional view of Fig. 1 taken along the line 5—5 thereof and viewed in the direction of the arrows;

Fig. 6 is a schematic plan view of Fig. 1 showing the manner of interconnecting the various electrodes with the contact pins of the tube;

Fig. 7 is a perspective view of a modification of the composite electrode of Fig. 3;

2

Fig. 8 is a perspective view of another modification of the composite electrode of Fig. 3.

Referring to Fig. 1, there is shown any well known form of enclosing bulb or envelope 10 of glass or other suitable material closed off at its lower end by a button header 11 through which are sealed the various lead-in wires or contact pins 12—19. The inner ends of these pins are connected to respective electrodes of an electron-tube mount 20, these connections being schematically illustrated in Fig. 6. The mount may comprise, for example, an electron emitting cathode which may be either of the filamentary kind or of the indirectly heated kind. In the particular tube shown in the drawing, the cathode 21 comprises a heatable filament coated on its exterior surface with any well known kind of electron emissive material. The filament is connected to a metal pin 23 centrally sealed in the header 11 and electrically connected to another pin 16. The central pin 23 does not extend externally of the header 11. The upper end of the filament 22 is anchored to a metal tab 24 to maintain the filament under suitable tension.

Surrounding the cathode are two grid electrodes 25, 26. These grids may be of any well known construction, for example each may be in the form of a fine wire helically wound around a pair of spaced parallel uprights or grid side rods 27, 28, and 29, 30 (see Fig. 2). These side rods are omitted from Fig. 1 for the purpose of clarity in the drawing. While the drawing shows grids 25 and 26 as of elliptical contour in plan view, this contour may be circular or other desired shape. The grid turns extending between the respective side rods to which they are anchored are known as grid laterals. Preferably the grids are wound and supported so that the laterals of the two grids are in alignment.

Located on opposite sides of the two grids are two anodes 31, 32, each for example in the form of a flat metal strip, these anodes being located in symmetrical alignment with each other and with the cathode 21. Each of the anodes is enclosed or surrounded by a composite beam-defining and secondary electron suppressor plate 33, 34. One of these plates, namely plate 33 for the anode 31 is shown in enlarged perspective form in Fig. 3. Each of these plates is formed from a flat metal strip, the end sections 35, 36 of which are bent back towards each other to form a substantially semi-cylindrical tubular unit. The flat front face 37 of this unit is provided with an elongated window 38 centrally thereof and located in alignment with the corresponding anode 31. The flat central portion 37 is also provided at opposite ends with integral wings 39, 40 for purposes to be described. If desired the bent back wing portions 35 and 36 can be welded or otherwise united at their abutting edges. The wings 39, 40 extend substantially beyond the ends of all the electrodes and thus serve as end shields for electrostatically shielding the ends of the anodes from the grids and cathode.

As shown in Fig. 1, the various electrodes are assembled as a unitary mount between a pair of insulator spacer discs such as the bottom mica disc 41 and the top mica disc 42. Each of these micas has a central opening through which pass the corresponding ends of the cathode 21. These micas also have respective openings to receive the ends of the grid side rods 27—30, which by any well known means can be anchored against longitudinal movement. The micas also have slots to receive the wings 39, 40 of electrode 33 and the similar wings 43, 44 of electrode 34. The micas 41, 42 also have slots to receive the respective ends of anodes 31, 32. The projecting upper ends of these anodes are electrically connected by a U-shaped metal strap 45. Welded or otherwise fastened to the projecting wings 39 and 43 and bearing against the mica 42 is a channel-shaped metal

strip 46 (see Fig. 4) which has at one end a struck-up portion which forms the filament anchoring lug 24 hereinabove mentioned. A fine wire filament tensioning spring 47 is welded to the lug 24 and to the upper end of filament 21. The opposite side of member 46 has a downwardly struck tab which fits into a corresponding slot in the edge of mica 42. The bottom wall of member 46 has a rectangular window 48 through which the cathode sleeve and the grid side rods project so as to prevent the short circuiting thereof by member 46. A similar channel-shaped metal member 49 is fastened to the wings 40, 44 at the lower ends of electrodes 33 and 34.

If desired, the lower member 49 may have attached thereto a downwardly depending lug 50 which extends downwardly between the anode lead-in member and the adjacent grid lead-in member to complete the shielding therebetween.

A suitable getter unit 51 may be attached to the upper member 46 so that when the gettering material is flashed the deposit is confined to the upper end of the interior surface of bulb 10.

The manner of connecting the various electrodes to the respective lead-ins or pins 12-19 is schematically illustrated in Fig. 6. When the tube is to be used as a pentode, the first grid 25 acts as a control grid and the second grid acts as a shield grid. The electrodes 33 and 34 act as complete electrostatic shields for shielding the respective anodes from the associated grids and also they serve as collector electrodes for secondary electrons which may be emitted from the respective anodes. Furthermore, the windows 38 and 52 in these composite shielding and suppressor electrodes act in the nature of beam-defining windows.

From the foregoing it will be seen that the anodes are substantially completely shielded from the associated grids without the necessity of employing an external shield which ordinarily surrounds the interelectrode space. As will be seen from Fig. 1 of the drawing, the finally assembled mount is completely open to inspection in the space between the electrodes 33 and 34, thus enabling the alignment of the grids to be readily observed and adjusted if necessary. Furthermore, by combining the outer shield and beam plate as a single element, the cost of manufacture and assembly of the tube can be reduced while permitting pentode tubes of small or miniature size to be manufactured economically.

If desired, the windows 38 and 52 in each of the composite beam plate and shielding electrodes can be formed with integral wings so as further to define the electron beam reaching the respective anode. Such a modification is shown in Fig. 7, wherein the parts corresponding to those of Fig. 3 carry the same designation numerals. As will be seen in Fig. 7, the member 33 is formed with integral diverging strips or wings 53, 54 along the edges of the window 38. While Fig. 7 shows these wings diverging outwardly in a direction facing the cathode, it will be understood that they may be located interiorly of the member 33 facing the respective anode.

The invention is not limited to any particular number or arrangement of the beam-defining windows 38. For example, as shown in Fig. 8, the composite electrode 33, instead of being formed with a single longitudinally extending window, may be provided with a series of laterally extending windows 55.

While the invention has been described particularly in connection with a so-called pentode tube, it will be understood that the composite beam-defining and shielding electrode, such as shown in Figs. 3, 7, and 8, may be used in other types of electron tubes. Similarly, while the tube has been shown as embodying a so-called filamentary cathode, it will be understood that this cathode may be of the so-called indirectly heated type, including a cathode sleeve with an internal heater element or filament.

What is claimed is:

1. An electron tube comprising, cathode means to de-

velop an electron stream to be controlled, an anode upon which the electron stream terminates, and a composite electrostatic shielding and electron stream-passing electrode within said tube, said electrode substantially surrounding said anode but having a beam-passing aperture facing the cathode means.

2. An electron tube comprising a cathode to develop an electron stream to be controlled, a pair of discrete anodes disposed on opposite sides of and in a plane including said cathode, and discrete electrostatic shielding electrodes each individually electrostatically isolating a corresponding anode except for a portion of the wall thereof which is provided with a window on the side facing the cathode to permit the electron stream to pass from the cathode to the anode.

3. An electron tube comprising a cathode to develop an electron stream to be controlled, a pair of discrete anodes disposed on opposite sides of and in a plane including said cathode, at least one control grid located between said cathode and anodes, and a pair of discrete composite shielding and secondary emission collector electrodes each individually electrostatically isolating a corresponding anode from said grid except for a beam-passing window therein through which the electron stream passes from the cathode to the anode.

4. An electron tube comprising an elongated cathode to develop electron beams extending therefrom in opposite directions, at least one control grid surrounding said cathode, a pair of discrete anodes located on opposite sides of said control grid in alignment with said cathode, and a pair of shielding plates each substantially enclosing only a corresponding one of said anodes, said shielding plates each having a beam-passing window facing said cathode.

5. An electron tube according to claim 4, in which each of said shielding plates has a longitudinal window having its length substantially parallel to the length of the cathode.

6. An electron tube according to claim 4, in which each of said shielding plates has a pair of diverging wings at the edges of the beam-passing window therein.

7. An electron tube according to claim 4, in which each of said shielding plates has a plurality of beam-passing windows extending transversely to the length of the cathode.

8. An electron tube according to claim 4, in which each of said shielding plates has at its opposite ends wings for shielding the respective ends of the anodes from the corresponding ends of the grid.

9. An electron tube mount comprising a pair of insulator spacers between which a plurality of electrodes are mounted, said plurality of electrodes including a central elongated cathode, a pair of grids surrounding the cathode, said grids having respective side rods located in substantially the same plane with said cathode, a pair of discrete anodes located on opposite sides of the cathode, and a pair of discrete and approximately tubular electrostatic shielding plates each surrounding a respective one of the anodes alone, each of said tubular plates having at least one beam-defining window therein for the electrons passing between the cathode and anode.

10. In combination, a composite anode-shielding and beam-defining electrode for electron tubes, comprising a sheet metal element of substantially tubular shape and having at least one elongated beam-defining window therein, and an anode within said electrode, said window providing communication to said anode from the exterior of said electrode.

11. A composite electrode according to claim 10 in which the beam-defining window extends along the length of the electrode.

12. A composite electrode according to claim 10 in which said element is formed with integral shielding wings extending therefrom.

13. A composite anode-shielding and beam-defining electrode for electron tubes, comprising a sheet metal element of substantially tubular shape and having a

plurality of beam-defining windows extending transversely to the length of said electrodes.

14. In combination, a flat anode, a cathode and a tubular electrostatic shielding and beam forming member surrounding said anode, and having a flat portion extending between said cathode and anode, and in a plane parallel to said anode, said flat portion having a window therein to provide a straight line electron communication between said anode and cathode in a direction normal to said anode.
